UNITED STATES PATENT OFFICE.

JOSEPH HODGSON, OF PHILADELPHIA, PENNSYLVANIA, ASSIGNOR TO THOMAS DOLAN, OF SAME PLACE.

DESIGN FOR SHAWLS.

Specification forming part of Design No. 5,736, dated April 2, 1872.

Specification describing a Design for a Shawl-Fabric, produced or invented by JOSEPH HODGSON, of Philadelphia, county of Philadelphia, and State of Pennsylvania.

Design for a Shawl-Fabric.

The nature of the invention is represented in the accompanying drawings, in which—Figure 1 shows a portion of the shawl-fabric, Fig. 2 illustrating the style of part of the fabric.

The pattern consists of stripes A A A, of cassimere-twill fabric, represented on an enlarged scale in Fig. 2; and stripes B B', ornamented as shown. The stripes may be varied as regards width and color.

I claim as my invention—

The design for a shawl-fabric, substantially as herein described, and illustrated in and by the accompanying drawing.

In testimony whereof I have signed my name to this specification in the presence of two subscribing witnesses.

JOSEPH HODGSON.
